UNITED STATES PATENT OFFICE.

FRANK K. RICH AND MATTHEW G. MARSH, OF EAST EDDINGTON, MAINE.

TOY.

1,060,631.

Specification of Letters Patent.

Patented May 6, 1913.

Application filed September 28, 1911. Serial No. 651,734.

To all whom it may concern:

Be it known that we, FRANK K. RICH and MATTHEW G. MARSH, citizens of the United States, and residents of East Eddington, in the county of Penobscot and State of Maine, have invented certain new and useful Improvements in Toys, of which the following is a specification, reference being had to the accompanying drawings.

10 This invention relates to amusement devices and comprises a ring designed to be worn by children and others for their amusement, and carrying for this purpose a pin-wheel which will be caused to revolve 15 by the natural movement of the hand in walking.

The object of the invention is further to provide an attractive and noticeable device of this type which may be manufactured at 20 such a low cost that it may be used for advertising purposes or cheaply sold to children for their amusement.

With these and other objects in view the present invention consists in the combination 25 and arrangement of parts as will be hereinafter more fully described and finally pointed out in the appended claims, it being further understood that changes in the specific structure shown and described may 30 be made within the scope of the claims, without departing from the spirit of the invention.

In the accompanying drawings forming a part of this specification and in which like 35 numerals of reference indicate similar parts in the several views: Figure 1, is a perspective view of the device in use. Fig. 2, is a view partly in elevation and partly in section of the said device. Fig. 3, is a plan 40 view of the device. Fig. 4, is a plan view of the blank from which the pin-wheel member of the device is formed.

In the drawings, the device is illustrated 45 as consisting primarily of a finger ring which is indicated by the numeral 1, and which may be plain or ornamental, as desired. At a point in its circumference, the ring is formed with an opening 2, which is preferably increased in diameter in the direction of the axis of the ring to form a 50 splayed opening. A tubular shank 3, is fitted at one end into this splayed opening and flanged therein, as indicated by the numeral 4. This shank 3, is flared at its outer end 55 to form a head 5, which presents a flat up-

per riding surface, and has its edge flanged downwardly.

The pin-wheel which is carried by the ring is formed from the blank 7, shown in Fig. 4, of the drawings, and has a central pin 60 opening 6, and the edge openings 5'. This blank is of rectangular form, primarily, and is indicated by the numeral 7, and is formed with slits 8, extending inwardly toward its center from each corner. These slits 8, terminate short of the said central opening 6, of the blank, as shown in the said Fig. 4, and the portions between the slits are folded over to form four wings, in the manner shown in Figs. 1, 2, and 3. A pin 9, is inserted through the pin openings 5', at the corners of the wing forming portions of the blank and through the center opening 6, and this pin is provided at its outer end with a head 10, and has its inner end flattened, 70 as at 11, to form a chisel edged end at the inner end of the pin. The inner flattened head 11, is of a diameter slightly less than the inner diameter of the shank 3, as shown in Fig. 2.

In order to hold the pin in position within the tubular shank 3, this shank is filled with cement sealing wax or other like substance, into which while in a plastic condition the flattened chisel edged end 11, is forced. When the substance hardens, the 80 pin is firmly secured in position. The plastic substance in effect forms a bushing when solidified. It will be readily understood that the pin-wheel thus formed is mounted 85 for revolution upon the pin 9, and that when the ring is worn, the natural movement of the hand will cause the pin-wheel to revolve.

It will of course be understood that the 90 pin-wheel itself may be made of any suitable material, such for example as celluloid, sheet metal, or the like, and that the different vanes of the wheel may be differently colored or coated with an iridescent substance so as to produce a dazzling effect as 95 the wheel revolves.

From the foregoing it will be understood 100 that the device will afford considerable amusement and that it may be manufactured at a nominal cost.

Having thus described our said invention, what we claim as new and desire to secure by United States Letters Patent is:

1. The combination with a finger ring having a splayed opening, of a tubular 110

shank having one end flanged into said splayed opening the outer end being flared to provide a flat riding surface having a downwardly flanged edge, a pin having a head and held within the bore of said shank, and a pin wheel upon said pin and revolving upon said flat riding surface, as and in the manner set forth.

2. The combination with a finger ring having a splayed opening, of a tubular shank having one end flanged into said splayed opening the outer end of said shank being flared outward to provide a flat riding surface ending in a downwardly flanged

edge, a cement mixture within said shank 15 bore, a pin having a head and chiseled end forced into said cement while plastic, and a pin-wheel held upon said pin and revolving upon said flat riding surface, as and in the manner set forth.

20 In testimony whereof, we affix our signatures in presence of two witnesses.

FRANK K. RICH.
MATTHEW G. MARSH.
